APPARATUS FOR RENDERING AND
REFINING FATS

Charles B. Upton, Piqua, Ohio

Application August 2, 1933, Serial No. 683,348

6 Claims. (Cl. 87—13)

This invention relates to the rendering of fats and the like, in which fat and oil yielding materials are subjected to heat treatment so as to liberate free grease or oils. Heretofore it has been a common practice to render fats, such as lards, by subjecting fat or oil bearing substances to heat treatment, and the liberated grease or oil was then removed and separately treated and refined to place it in marketable condition.

10 An object of this invention is to provide an improved rendering and refining kettle in which the fats are rendered and the oils and greases liberated therefrom are refined, all in one apparatus and in concurrent operations; with which 15 the rendering and refining operations may be carried on with a minimum of handling of the materials; which will occupy a minimum of floor space; with which the cooking and refining operations may be carried out in a minimum of 20 time and with a minimum of effort; with which the cooking conditions may be changed at will; with which the cooking may be carried on at, above, or below atmospheric pressure as may be desired; with which the solids and residue from 25 the rendering chamber may be easily discharged at the conclusion of a rendering operation without admixture with the refining solids, and vice versa; with which the free grease or oil rendered from the products will be immediately removed 30 from contact with the fibres of the material being rendered; with which the liberated greases and oils will pick up a minimum of protein and mucilaginous materials; with which moisture may be removed from the material being rendered and 35 also from the free grease during the cooking operation; and which will be relatively simple and inexpensive.

Another object of the invention is to provide 40 improved means for rendering and refining oils and greases in a complete process and in one self contained unit.

Various other objects and advantages will be 45 apparent from the following description of one embodiment of the invention, and the novel features will be particularly pointed out hereinafter in connection with the appended claims.

In the accompanying drawing:

Fig. 1 is a sectional elevation through a rendering unit constructed in accordance with this invention;

Fig. 2 is a sectional plan of the same, the section being taken approximately along the line 2—2 of Fig. 1;

Fig. 3 is a sectional plan, on a larger scale, of a 55 portion of the floor of the upper compartment, to

illustrate one of the screens for the drainage openings; and

Fig. 4 is a sectional elevation, of the same portion of the floor of the upper compartment, the section being taken approximately along the line 5 4—4 of Fig. 3.

In the illustrated embodiment of the invention, the improved rendering and refining kettle includes an upright casing 10, which may be formed of superposed sections connected together 10 to form a unit, and having intermediate of its ends a transverse wall or partition 11 which subdivides the interior of the casing into a cooking or rendering chamber or compartment 12 and a refining chamber or compartment 13, the two 15 chambers or compartments being thus superposed with respect to one another and separated by the wall or partition 11 which forms the floor of the upper compartment and the top of the lower compartment.

The sides and bottom of the casing 10 are steam jacketed, in a manner common in this art, both above and below the floor wall or partition 11, and this floor or wall 11 is also, preferably, similarly steam jacketed. The joints between 20 abutting sections of the casing are made airtight, and for this purpose the abutting faces of the sections may have cooperating ribs and grooves, with suitable gasket material disposed in the bottom of each groove to provide an effective seal at the joints. The sections may be coupled in any suitable manner, such as by screws or bolts, as shown. The top portion of the casing may have a charging dome 14 which is 25 suitably closed by a cover 15, the cover, when closed, being sealed against the open end of the dome 14 with interposed gasket material, by draw bolts or rods 16 with adjustable nuts 16a, the bolts being pivoted to suitable lugs on the dome 11 and swung into and out of position for 30 engagement with the cover through suitable slots 17 in the periphery of the cover.

A vent pipe 18 opens into the upper compartment 12 through the dome 14, and carries a 35 pressure gauge 19. The pipe 18 has a branch pipe 20 opening into atmosphere and controlled by a valve 21, so that any pressure in the casing may be released by opening the valve 21, or the escape of air or other gases may be shut off 40 through the closing of the valve 21. The pipe 18 also is connected through a valve 22 to a barometric condenser 23, or other device for creating a partial vacuum or suction, so that by closing the valve 21 and opening the valve 22 a 45 50 55

partial vacuum may be created in the cooking chamber or compartment 12 of the casing.

The floor wall or partition 11 is provided with a plurality of drainage passages 24, extending 5 from face to face of the wall 11, so as to establish continuous communication between the upper or cooking compartment 12 and the lower or refining compartment 13. Each of these passages 24 is screened at its upper end by a per- 10 forated plate 25 which is countersunk flush into the upper face of the floor wall 11 and secured against displacement by countersunk screws 26. The perforations 27 of the plate 25 are large 15 enough to allow free grease and oils to pass through without material opposition, but are small enough so that very little, if any, of the solids or fibres of the material being rendered will pass through the plate.

A drain pipe 28 opens upwardly through the 20 bottom of the casing, which is the bottom or floor of the lower or refining compartment 13, into the refining compartment, and is controlled by valve 29 so that when the valve 29 is opened, free grease or oil in the refining chamber may 25 flow off and be collected in any suitable receptacle, not shown. The casing 10 is also provided with a pair of door openings 30 and 31, one for 30 each of the compartments 12 and 13 respectively. These door openings extend upwardly some distance from the floor of the compartment and are entirely separate from, and out of communication with, one another. A door or closure 32 is fitted to the casing so as to close the door opening 30 and make an air tight closure therewith, 35 yet this door 32 is operable into open position as will be explained presently. Similarly a door or closure 33 is fitted to the casing so as to close the door opening 31 in the wall of the refining compartment 13, and is operable, when desired, into 40 open position so as to establish communication with the interior of the casing through the door opening 31.

A driving shaft 34 extends into the casing, and for convenience may extend upwardly through 45 the bottom wall thereof. The space between the shaft 34 and the bearing in the lower wall may be sealed by a suitable packing gland 35. This shaft 34 also extends through an opening 36 in the floor wall or partition 11 and is rotatably 50 mounted at its upper end in a bearing 37 which is supported by projections or a spider-like frame provided on the interior of the casing. The shaft 34 mounts an agitator blade 38 within the lower compartment 13, and also an agitator blade 39 55 in the cooking compartment 12. The blades 38 and 39 are fixed to the shaft so as to rotate therewith and are so disposed as to move in close proximity to, or sweep the floor of the compartments in which they are placed and move any 60 solid matter in these compartments toward the door opening of that compartment.

The shaft 34 also carries another blade 40 in the upper part of the compartment 12, and this blade 40 may have a plurality of fins or project- 65 ing arms 41 thereon to assist in the agitation. Arms 42 may also connect the blades 39 and 40 so as to act as stirrers moving through the interior of the mass of fats or substances being cooked or rendered in the upper compartment 70 12. The shaft 34 is rotated in any suitable manner, such as by any suitable motor or other source of power, not shown, and when rotated will keep the contents of both compartments agitated. When the doors 32 and 33 are opened, the blades 75 or agitators 38 and 39 in the compartments will

shift the solids of those compartments to and through the respective door openings of those compartments.

The cooking chamber or compartment 12 and the refining or drainage compartment or chamber 13 are both of substantial depth, and at the beginning of or preceding the operation of rendering a batch of material, a refining agent of any desirable character is introduced into the lower or refining compartment 13 through a suitable pipe connection 13a in the side of the casing. For example, activated carbon, soda and other chemicals may be placed in the lower compartment 13, and as the free grease or oil drains into the lower compartment through the passage 24 from the upper cooking or rendering compartment, it will be thoroughly mixed with the activated carbon and other refining agents or chemicals.

At the conclusion of the rendering operation, 20 the valve 29 can be opened and the free oil or grease in the refining compartment can be drawn off, filtered through a filter press to remove the activated carbon, and the grease is then in a marketable condition, after which the cracklings or solids in the upper or cooking compartment 12 may be discharged through the door opening 30 by the operation of the agitator 39 which sweeps the solids or cracklings toward and through the door opening 30. Thereafter any 30 fine solids which work through the perforations 27 in the drainage plates 25 into the lower compartment, together with the activated carbon and other chemical agents, still remaining in the compartment 13, can be similarly discharged 35 through the door opening 31. With this arrangement the cracklings will be kept separate from the activated carbon and other refining substances, and thereby the cracklings will bring a 40 higher price than when mixed with the activated carbon or other refining materials.

In operation, the refining agent, such as activated carbon, soda and other chemicals, are placed in the lower compartment 13 and the door 33 thereof tightly closed. The door 32 is similarly closed and a charge of fats or other materials to be rendered is introduced through the dome 14 after the cover 15 has been removed. After the charge has been placed in the cooking chamber 12, the cover 15 will be tightly closed 50 again, and heat turned on in the steam jacketed walls of both chambers and the steam jacketed floor or wall 11. The valve 29 is closed and, as the cooking continues, the temperature of the mass in the cooking chamber will be kept uniform throughout the mass by the action of the agitators therein. By suitable manipulation of the valves 21 and 22, the internal pressure conditions within the casing may be regulated as desired, and as the cooking continues, free grease 55 or oil will be liberated and will drain promptly through the perforated plates 25 in the refining compartment 13, before this free grease or oil has had a chance, through prolonged contact with the material in the upper compartment, to pick up protein or other mucilaginous materials. As rapidly as the oil and free grease drains into the lower compartment, it is thoroughly mixed 60 with the heated refining agents, such as activated carbon, soda and other chemicals, and refined and kept hot or fluid. After all of the free grease or oil has been liberated from the mass in the upper compartment 12, and has been drained into the refining chamber 13, the door 32 in chamber 65 12 may be opened, and then the continued move- 70 75

ment of the agitator 39 will sweep the residue, which commonly is called the cracklings, through the door opening 30, and after pressing the grease out of the cracklings, this residue or crackling 5 cake may then be sold as a by-product. During this discharge of cracklings, the oil or free grease in the compartment 13 is thoroughly mixed with the refining agent, and then the valve 29 may be opened to drain off the refined oil or free grease 10 which is now in a marketable or refined condition. After all of the oil or free grease has been drawn off from the chamber 13, the door 33 is opened, and the solid residue containing the activated 15 carbon is discharged through the door opening 31 and suitably disposed of.

It will be noted that with this arrangement, there will be no mixing of the cracklings with the activated carbon or other refining agents and, therefore, the maximum market price may be obtained 20 for the pure cracklings. If the activated carbon should be mixed with the cracklings, the cracklings would become dirty and black which would materially affect their sales value, although the quality of the cracklings, otherwise than in 25 appearance, would not be materially injured. It is also possible with this apparatus to perform any portion of the cooking operation under a partial vacuum which makes it possible to cook the mass at a lower temperature and to remove 30 the moisture from the material being rendered in the chamber 12, and also to remove the moisture from the material being rendered in the chamber 12, and also to remove moisture from the free grease that collects in the refining chamber 13. Thus, this apparatus is a self-contained 35 unit for the complete rendering and refinement of fats, such as lard.

It will be understood that various changes in the details, which have been herein described and 40 illustrated in order to explain the nature of the invention, may be made by those skilled in the art within the principle and scope of the invention as expressed in the appended claims.

I claim:

1. A rendering and refining kettle comprising a casing subdivided into superposed compartments of substantial depth, the upper compartment being of a size to hold a substantial charge of fat bearing solids, and the lower compartment being of a size to hold a charge of a solid refining agent and also all of the fats that can be liberated from said fat bearing solids, a separate air tight discharge door for each compartment adjacent the floor of that compartment for 45 discharging the contents of that compartment outside of the casing without passing through the other compartment, means for heating each compartment, the floor of the upper compartment having substantially flush with its upper surface 50 a screened drain opening into the lower compartment of a mesh to retain substantially all solids in the upper compartment and drain free grease released in the upper compartment continuously into the lower compartment, an agitator in each 55 compartment with a portion moving in close proximity to the floor of that compartment, and means for withdrawing free grease when desired from the lower compartment, whereby fats may be rendered in the upper compartment, the solids 60 all retained in that upper compartment, the free grease therefrom drained continuously into the lower compartment, there immediately mixed with solid refining materials, and at the end of the treatment of said charge of fat bearing 65 material, the refined fat may be withdrawn and 70
2. A rendering and refining kettle comprising a casing having steam jacketed walls, a steam jacketed, horizontal partition extending across the interior of the casing and subdividing it into a plurality of superposed compartments, said partition having a screened passage extending from face to face thereof, so that liquids may descend from the upper compartment to the lower, and practically all solids in the upper compartment will be retained therein, a valve controlled pipe opening into the lower compartment at the floor 75 thereof to remove free grease therefrom at intervals, said casing having in a side wall thereof a pair of individual doors, one for each compartment and opening into that compartment at the floor thereof, and an agitator in each compartment and approximately sweeping the floor thereof so as to sweep the contents of that compartment toward the door of that compartment, whereby fats may be rendered in the upper compartment, the free grease therefrom drained continuously into the lower compartment and there treated with refining solids and chemicals, all in one concurrent operation, and the solids in each compartment afterwards discharged from the casing separately from one another.
3. A rendering and refining kettle comprising a casing having steam jacketed walls, a steam-jacketed, horizontal partition extending across the interior of the casing and subdividing it into a plurality of superposed compartments, said partition having a screened passage extending from face to face thereof, so that liquids may descend from the upper compartment to the lower, and practically all solids in the upper compartment will be retained therein, a valve controlled pipe opening into the lower compartment at the floor 40 thereof to remove free grease therefrom at intervals, said casing having in a side wall thereof a pair of individual doors, one for each compartment and opening into that compartment at the floor thereof, an agitator in each compartment and approximately sweeping the floor thereof so as to sweep the contents of that compartment toward the door of that compartment, whereby 45 fats may be rendered in the upper compartment, the free grease therefrom drained continuously into the lower compartment and there treated with refining solids and chemicals, all in one concurrent operation, and the solids in each compartment afterwards discharged from the casing 50 separately from one another, a valve controlled vent for said casing by which an internal pressure at or above atmospheric pressure may be created within said casing during a cooking operation, and means also connected to said casing for 55 creating a partial vacuum therein at will.
4. A one-stage, lard rendering and refining kettle, comprising a plurality of heated chambers arranged at different levels, the upper of said chambers being of a size to hold a substantial charge of fat bearing materials, and the lower chamber being of a size sufficient to hold all of the free fat liberated from said charge and also a charge of a solid refining agent, a passage opening through the floor of the upper chamber, and leading to the lower chamber, a screen across said passage and forming a continuation of the floor across said passage, said screen having a mesh of such fineness that it passes liquefied fats and 60 prevents passage of any substantial amount of 65

filtered to separate it from some of the refining materials, and the solids of said compartments removed separately and without mixing with one another.

5

2. A rendering and refining kettle comprising a casing having steam jacketed walls, a steam jacketed, horizontal partition extending across the interior of the casing and subdividing it into a plurality of superposed compartments, said partition having a screened passage extending from face to face thereof, so that liquids may descend from the upper compartment to the lower, and practically all solids in the upper compartment will be retained therein, a valve controlled pipe opening into the lower compartment at the floor 10 thereof to remove free grease therefrom at intervals, said casing having in a side wall thereof a pair of individual doors, one for each compartment and opening into that compartment at the floor thereof, and an agitator in each compartment and approximately sweeping the floor thereof so as to sweep the contents of that compartment toward the door of that compartment, whereby fats may be rendered in the upper compartment, the free grease therefrom drained continuously into the lower compartment and there treated with refining solids and chemicals, all in one concurrent operation, and the solids in each compartment afterwards discharged from the casing 15 separately from one another.

20

3. A rendering and refining kettle comprising a casing having steam jacketed walls, a steam-jacketed, horizontal partition extending across the interior of the casing and subdividing it into a plurality of superposed compartments, said partition having a screened passage extending from face to face thereof, so that liquids may descend from the upper compartment to the lower, and practically all solids in the upper compartment will be retained therein, a valve controlled pipe opening into the lower compartment at the floor 25 thereof to remove free grease therefrom at intervals, said casing having in a side wall thereof a pair of individual doors, one for each compartment and opening into that compartment at the floor thereof, an agitator in each compartment and approximately sweeping the floor thereof so as to sweep the contents of that compartment toward the door of that compartment, whereby 30 fats may be rendered in the upper compartment, the free grease therefrom drained continuously into the lower compartment and there treated with refining solids and chemicals, all in one concurrent operation, and the solids in each compartment afterwards discharged from the casing separately from one another.

35

4. A rendering and refining kettle comprising a casing having steam jacketed walls, a steam-jacketed, horizontal partition extending across the interior of the casing and subdividing it into a plurality of superposed compartments, said partition having a screened passage extending from face to face thereof, so that liquids may descend from the upper compartment to the lower, and practically all solids in the upper compartment will be retained therein, a valve controlled pipe opening into the lower compartment at the floor 40 thereof to remove free grease therefrom at intervals, said casing having in a side wall thereof a pair of individual doors, one for each compartment and opening into that compartment at the floor thereof, an agitator in each compartment and approximately sweeping the floor thereof so as to sweep the contents of that compartment toward the door of that compartment, whereby 45 fats may be rendered in the upper compartment, the free grease therefrom drained continuously into the lower compartment and there treated with refining solids and chemicals, all in one concurrent operation, and the solids in each compartment afterwards discharged from the casing 50 separately from one another, a valve controlled vent for said casing by which an internal pressure at or above atmospheric pressure may be created within said casing during a cooking operation, and means also connected to said casing for 55 creating a partial vacuum therein at will.
